VALERIAN IVANOVITSCH BASHENOFF, OF MOSCOW, RUSSIA.

METHOD AND ARRANGEMENT FOR THE MULTIPLE AND DIRECTED RECEIVING OF RADIOSIGNALS.

Application filed June 18, 1923, Serial No. 646,160, and in Germany June 20, 1922.

Stations for directed receiving have already become known in which either a great number of directing open antennæ arranged at different angles or coil antennæ in pivotable frames are used.

The known arrangements of this type have however several inconveniences some of which will be mentioned hereafter and which are to be avoided by this invention.

- 10 In the ring receiving stations which have become known a plurality of open antenna-circuits are arranged at different angles so that the earth forms part of the circuit, whereby on the one hand the intensity and 15 the precision of the tuning in the receiver is considerably influenced and on the other hand the intensity of the tuning becomes different for the several antennæ circuits as the antenna-decrement is dependent on the 20 carrying condition of the ground.

Bellini and Tozi have proposed a directed receiving station after the radio goniometric principle with only two frame antennæ crossed at an angle of 90°. But the working with such stations is rather bothersome. The two independent antennæ have to be adjusted carefully, to be accurately tuned, the frequency and the damping of the same has to be absolutely alike. The induction coupling between the two induction coils and the neutralizing of disturbing currents is also very difficult.

The frame receivers commonly used possess the inconvenience that, owing to weak 35 receiving, they require considerable amplification and that they represent besides an asymmetric receiver, e. g. the two maxima are not equal and the angle between the minima of audibility deviates from 180° as careful tests have shown. The frame receivers 40 can therefore not be called reliable directing apparatus.

The invention has for its object to obviate or at least to reduce the inconveniences of 45 the known systems and with this object in view a middle course is proposed which consists in utilizing a plurality of closed antenna circuits of large cross section and of low number of turns, said circuits being

arranged at angles with regard to one another and radially with regard to the support, said antenna circuits being directed upon the determined sending station and adapted to be connected in a manner known per se with a separate receiving circuit or 55 with a separate testing circuit.

In comparison with the well known ring-receiving stations, which are most like the object of the invention the advantage is obtained that the effect in the receiving 60 set is considerably greater and independent of the condition of the ground owing to the use of closed circuits.

Compared with the directed receiving system of Bellini and Tozi the invention has 65 the advantage that a multiple receiving becomes possible without difficulty as the mutual effects from induction are of secondary importance only. A much greater audibility is further ensured and all the other- 70 wise necessary very careful adjustments are avoided.

Compared with the frame coil receivers the improved system presents the advantages that, owing to the larger surfaces of 75 the closed receiving circuits, these circuits need only one or a few windings. The useful effective resistance is therefore much lower which is of special importance in receiving on short wave lengths wherefrom 80 results under otherwise equal amplification conditions a considerably greater intensity of sound in the telephone.

It has already been proposed about 15 years ago to use closed circuits for the general receiving but these proposals have had little results as it was not known that for multiple and efficient receiving it would be necessary to use circuits of large area and with a few windings only. This knowledge 85 discovered by the inventor has been confirmed by mathematical analysis and by practical experiences.

The invention will be best understood from a consideration of the following detailed description taken in connection with the accompanying drawings forming a part 95 of this specification, with the understanding

that while in the drawings different embodiments of the invention are disclosed, the invention is not confined to any strict conformity with the showing of the drawings, ⁵ but may be embodied in any manner which does not mark a material departure from the salient features of the invention.

The drawing represents a more or less schematic representation of a station with ¹⁰ umbrella-antenna transformed partly for directed receiving.

As shown in the drawing the right half of the station, of which only one open circuit is indicated by dotted lines, is not altered ¹⁵ but the station is adjusted by regulation of the capacity and induction of all circuits for the work to be done by means of one half of the net. In this half the receiving and sending of signals is carried out ²⁰ as usual during the whole time. The second half of the station has been transformed for directed receiving. At the upper end of the support, instead of the commonly used net-lines CD, lines A'M with counterpoises or ²⁵ electric balances hung up with the aid of insulators or, if the insulator of the existing station is of egg-shape, all the former wires with counterpoises are connected with a long insulator consisting of five to eight members ³⁰ the wires being connected in the intervals between the several members as shown on the drawing. The former net-wires CD are connected at the lower end of the support to a ring for counterpoises or to any other device, according to the system of the radio- ³⁵ station, by means of insulators arranged at the ends of the aerial-wires or, if the insulator of the existing radio-station is egg-shaped, all former wires of the aerial are connected with a long insulator composed of five to eight or more members in the intervals between the several members. The lower end M,c of each former counterpoise wire is electrically connected with the former aerial-wire situated in the same vertical plane.

The whole system is stretched at the point M by a pull wire (over a simple insulator or directly without such insulator as shown on ⁵⁰ the drawing) and attached to the pole P which formerly served as support for stretching wires of the aerials and counterpoise wires. By this arrangement each closed circuit is insulated from the other, the aerial ⁵⁵ of the radio-station being however not altered organically and adapted to be transformed at any time if necessary to an open circuit antenna. Each closed circuit consists of line A, line B,c connected to A at M, ⁶⁰ wire R connected to B,c and wire O connected to the upper end of line A, the testing or receiving set being inserted between the wires R and O.

From the upper end of each counterpoise ⁶⁵ wire A'M a separate connecting wire O is

conducted downward and similar connecting wires R are branched off from the lower ends of the circuits.

Any number of such circuits in accordance with the material at disposal (antenna ⁷⁰ wire) and in accordance with the required degree of accuracy of the determination of direction may be arranged. The opening angle of the circuit is optional and depends on the object to be attained. For general ⁷⁵ working, according to the improved working with n-circuits (the unknown radio stations searched for are situated as far as possible within an observation angle of 180°) the angle between the vertical circuits is so $\alpha = \frac{180}{n}$.

If the field of observation forms an angle of m-degree ($0 < m < 180$) all the n-vertical closed antenna circuits stand with regard to ⁸⁵ each other at an angular distance $\beta = \frac{m}{n}$ and the accuracy of observation becomes still greater. All connections O,R of the circuit are conducted in a manner known per se to ⁹⁰ corresponding terminals of a changing switch N so that each circuit, one after the other, may be inserted into the testing circuit. An adjustable condenser C₁ is connected with the two terminals of the changing switch N. In order to increase the area of the receiving waves in longitudinal direction the lengthening induction coil of the receiver may be inserted also in series.

It will be seen from the above that one of the objects of the invention is to provide for the utilization of the material available in the open circuit antennæ for the corresponding portion of the closed circuit antennæ. The right hand portion of the drawing ¹⁰⁰ which shows one open circuit antenna shows it to be composed of the antenna CD, the anchoring wire EF, which is insulatingly connected to one end of wire CD, and is connected to the post P at the other end, and the counterpoise or electric balance wire AB. These wires are insulated each from the other.

The left hand portion of the figure shows the manner in which the same material was utilized for the closed circuit antenna. The wire AM consists of the wires C'D', and E'F' that formerly served as open antenna and anchoring wire respectively. The wire BC which connects the points M, D, is the same as AB, which formerly served as a counterpoise or electric balance. Thus an umbrella shaped antenna having a plurality of open antenna wires is converted into the type of antenna described herein by utilizing the material of the open antennæ. When these changes are accomplished the inductances and capacities of the closed circuit antennæ must be maintained equal to the inductances and capacities of the open antennæ.

The telephone circuit is laid on the terminals of the condenser C_1 , a detector D and a block condenser C_2 being inserted in a manner known per se in said telephone circuit.

According to the improved method for observing the unknown radio wave the operator sits with the telephone on the ears and tries to ascertain, in rotating the condenser 10 C_1 and the changing switch N whether the unknown wave has started. If on any circuit he has ascertained this wave he tunes the condenser to a resonance with the arriving unknown wave and continues to work 15 exclusively with the changing switch in moving from one circuit to the other and in recording on the apparatus-register the number of the circuit and the corresponding audibility. The circuit at the switching-in 20 of which the maximal sound is obtained in the telephone is closest to the vertical plane which connects the unknown transmitting point of the waves with the centre of the aerial net of the receiving station which 25 makes the observations. This could be found out also from the minimum of the receiving strength with the aid of a parallel resistance. It is well known that the accuracy of such 30 observation is equal to the magnitude of the angle between the circuits. With five circuits for instance the precision i. e. the greatest possible error of the determination of the direction of the unknown radio-sta- 35 tion is $\frac{180}{5 \times 4} = 9^\circ$, with 10 circuits $\frac{180}{10 \times 4} = 4.5^\circ$ and so on, it being supposed that all circuits are uniformly distributed in the whole half circle.

It has been supposed above that only one 40 half of the normal umbrella-antenna is submitted to the transformation, all the elements of said umbrella-antenna being used for the composition of closed circuits required for the directed radio receiving. The 45 whole umbrella-antenna may however remain unaltered if closed circuits consisting of auxiliary wires are inserted between its open circuits. In this case the efficiency of the station in proportion to its normal work 50 (transmitting and receiving of radiograms) would not be diminished. In order to preserve the normal working method and to avoid a considerable mutual induction it is however better to arrange the umbrella- 55 antenna of all open circuits only upon one half of the circle by reducing the intervals, the other free half being however used for the closed circuits consisting of reserve antenna-conductors.

According to the wave length and distance 60 the closed circuits may consist of one or several windings inserted in series or in parallel.

The invention permits to utilize in this 65 manner all existing radio-stations at the

same time for searching the transmitting station. Special radiocompass stations may also serve for the general undirected receiving with corresponding arrangement according to the present invention and with the 70 aid of the same receiving apparatus which is used for the directed receiving. It has however to be taken into consideration that the capacity and the self inductance of the open aerials must be equal to that of the 75 closed circuit aerials so that the tuning of the open and closed aerials coincide at all wave lengths. The open or closed aerial may also be aperiodic for the same purpose.

The operator searches for the unknown 80 wave on the open aerial and after he has syntonized himself on this wave he goes over to the closed net with the aid of which the searching is executed as described above. The arrangement of the directed receiving 85 on stations of wireless telegraphy permits not only to determine the position (direction) of the corresponding radio-stations, but also to arrange for the selective and multiple receiving (e. g. the selective receiving under the most favorable conditions from 90 two or more stations which work simultaneously with one and the same waves or with different waves), provided the lines of direction of these stations form a sufficiently large angle with one another. If a station has several receivers it may be switched in simultaneously for several closed circuits to receive at once messages from 95 several stations.

In order to enable the simultaneous receiving from several radio-stations the lines of direction of which form a determined angle the one with the other it is sufficient 100 for the special case mentioned above to switch in each pair of opposite terminals of the changing-over switch, for instance with the aid of a plug, to the separate receiving circuit, of which a detailed description has 105 been given above (including C_1 , C_2 and T). In this case, when all plugs are switched out, and the changing over switch has been transferred from one circuit to the other the directed receiving from a radio-station takes 110 place. When however the changing over switch is at rest and all or some of the plugs are inserted the simultaneous receiving of 115 the work of several radio-stations (according to the number of the plugs inserted) takes place.

The invention permits also of the use of the duplex service.

I claim:—

1. An antenna device consisting in the combination of an open antenna for allround reception and transmission of signals with means for the multiple directed receiving of radio-signals, said means consisting of closed circuits of large area and a low number of windings for the simultaneous receiving of 120

- several signals from several stations, which work with different wave lengths, said circuits being radially arranged around the mast supporting the open antenna and 5 turned on the sending stations, from which messages have to be received each closed circuit being connected with a separate receiving-testing circuit.
2. An antenna device consisting in the 10 combination of an open antenna for allround reception and transmission of signals with means for the multiple directed receiving of radio-signals, said means consisting of closed circuits of large area and a low number of 15 windings for the simultaneous receiving of several signals from several stations, which work with different wave lengths, said circuits being radially arranged around the mast supporting the open antenna and 20 turned on the sending stations, from which messages have to be received, each closed circuit being connected with a separate receiving-testing circuit, a change-over switch by the switch arm of which the circuits for 25 directed reception may be successively inserted into one and the same receiving circuit.
3. An antenna device consisting in the 30 combination of an open umbrella antenna, the said umbrella antenna forming one half of the antenna device, the other half of the antenna device being formed of closed circuits differently tuned for the directed reception of different wave lengths emitted 35 from different stations, said closed circuits being formed in such a manner that the insulators between the antenna wire, the an-
- choring wire, and the electric balance wire of the open oscillatory circuit antenna are eliminated, the ends of the closed oscillation circuit being extended by means of convenient devices to two contact groups of a suitable change over switch, said contact groups being adapted to be connected in pairs with the terminals of the receiving circuit or of 40 a separate testing circuit.
4. An antenna device consisting in the 45 combination of an open antenna for allround reception and transmission of signals with means for the multiple directed receiving of radio-signals, said means consisting of closed circuits of large area and a low number of 50 windings for simultaneous receiving of several signals from several stations, which work with different wave lengths, said circuits being radially arranged around the common mast between the open circuits of 55 the normal radio-station.
5. An antenna device consisting in the 60 combination of an open antenna for all round reception and transmission of signals with means for the multiple directed receiving of radio signals, said means consisting of closed circuits of large area and a low 65 number of windings for the simultaneous receiving of several signals from several stations, said circuits being radially arranged around the mast supporting the open antenna, the capacity and the inductance of the several closed circuits and of the open antenna being equal.

Signed at Moscow this 29th day of May, 1923.

VALERIAN IVANOVITSCH BASHENOFF.
